[57] CLAIM

The ornamental design for a scissor clamp for logs, as shown and described.

DESCRIPTION

FIG. 1 is a front view of a scissor clamp for logs showing my new design, and shown in its closed state in gripping relationship with a log, shown in phantom, and further shown in association with support structure, also shown in phantom;

FIG. 2 is a side view thereof;

FIG. 3 is a top view thereof;

FIG. 4 is a front and side perspective view thereof; and,
FIG. 5 is a front view thereof in its open state, the rear view thereof being the same as said front view.
